W. S. EDSALL

MULTIBREAK ELECTRIC SWITCH

Filed April 1, 1925

UNITED STATES PATENT OFFICE.

WILLIAM S. EDSALL, OF BOSTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

MULTIBREAK ELECTRIC SWITCH.

Application filed April 1, 1925. Serial No. 19,990.

This invention relates to electric switches and particularly to that type of electric switch wherein the circuit is interrupted at a plurality of serially-connected points.

5 An object of this invention is the provision of an improved form of movable switch member especially characterized by a strong and rigid construction, particularly in the manner of supporting and electrically connecting the movable arcing members.

A further object of the invention is generally to improve the construction and operation of electric switches.

Certain features of this invention are disclosed in a co-pending application of Arthur C. Kelle, Serial No. 19,988, filed April 1, 1925, and assigned to Condit Electrical Manufacturing Company.

Fig. 1 is a perspective detail of the movable and stationary switch members of an electric switch in which the invention is incorporated.

Fig. 2 is a plan view of the movable switch member embodying the invention.

25 Fig. 3 is a side elevation of Fig. 2.

Fig. 4 is an end elevation of Fig. 2.

Fig. 5 is a section along line 5—5 of Fig. 2.

Fig. 6 is a sectional detail along line 6—6 of Fig. 2.

30 The electric switch with which the invention is particularly concerned includes the stationary switch members 10 and 12 which terminate in inverted brush members 14 and 16. Said brush members are adapted to be bridged by the movable bridging member and carry the current. Brackets 18 and 20 are fixed to and are electrically connected with the lower ends of said switch members and are extended laterally from similar

40 sides thereof, and depending and outwardly reflexed stationary arcing members 22 and 24 are fixed detachably to and are electrically connected with said brackets. An insulating pillar 26 is disposed on the opposite side of said stationary switch members; and a horizontally disposed and electrically-conducting bar 28 is fixed to the lower end of said pillar. Arcing members 30 and 32, similar to the arcing members 22 and 24

45 are fixed detachably to and are electrically connected with said bar and extend downwardly and outwardly therefrom. The spacing of the arcing members is such that

the brush members are disposed substantially midway between them.

55 Said arcing members are adapted to be connected in series by arcing members carried by the movable switch member, whereby to draw four circuit-interrupting arcs in series.

The movable switch member includes an insulated supporting rod 34 which is disposed for movement in a vertical direction between the brush members. A supporting member or bracket 36 is fixed to the lower end of said rod and includes a horizontally-disposed plate 38. Spaced arms 39 and 40 are formed integrally with said plate and extend downwardly and outwardly in the same direction from said plate; and similar arms 42 and 44 extend downwardly and outwardly from said plate in the opposite direction. Said arms are adapted to support the movable arcing members.

75 The movable bridging member comprises a plurality of parallel bars 46 arranged on edge and disposed beneath said plate 38 and between said arms. Said bars are pivoted on a pivot pin 48 which extends loosely through the middle of said bars and is supported in said arms. Said bars may be maintained in relatively closely spaced relation by spacing discs 50 disposed on said pin. Said bars are adapted to engage the brush members 14 and 16 and thereby bridge and carry the current between them. A slight amount of pivotal movement is permitted of the bars, whereby each bar may independently adjust itself in contact with the brush members; and said plate 38 is adapted to limit the extent of pivotal movement.

95 The supporting means for the movable arcing members includes the two rods 54 and 56. Said rods are here shown as approximately square in cross-section and each is formed with the square metal bar 58 and the square insulating enclosing sheath 60 having a side wall of substantial thickness. The ends of said pairs of arms 39, 40; and 100 42, 44 are formed with aligned square apertures 62 therein and said rods are received in the apertures in said arms and extend outwardly beyond and on opposite sides of said arms. Slots 64 extend through the ends 105 of said arms into said apertures and bolts 66

are passed through the slotted ends, whereby to clamp said rods firmly to said arms.

The ends of the square conducting bars 58 of said insulated rods 54 and 56 extend outwardly beyond the insulating sheaths 60 thereof and the movable arcing members 68, 70, 72, 74 are carried by said exposed ends.

Said arcing members are similar in construction and include contact members 75 each of which is fixed to the upper end of a laminated resilient conducting member 76, which member may be formed with the struck-out portion 78 intermediate its ends 15 whereby to provide increased flexibility to said member. The lower end of said member is fixed to and electrically connected with an attaching member 80 and said attaching member has a projection 82 which is adapted 20 to overlie said conducting member 76 and engage it between said struck-out portion and the arcing member whereby to restrict its flexing movement in one direction. A flat spring member 84 may be disposed to 25 engage said conducting member on the other side thereof whereby to provide a yielding support therefor.

Said attaching member is formed with a square aperture in which the exposed end 30 of one of said rods 58 is adapted to be received. A slot 86 may extend into said aperture and the slotted end of the attaching member may be clamped removably in position on said rod 58 by a bolt 88. Preferably said rod 58 is notched and said bolt 35 88 is disposed in the notch whereby positively to secure the arcing member in place.

As thus arranged the arcing members are arranged in pairs and the arcing members 40 of each pair are supported rigidly and electrically connected by one of said rods 58, while all of said arcing members are insulated from the supporting bracket 36 by the insulating sheaths 60.

45 The square cross-section of the insulated rods provides a construction which prevents the rotation of the rods, or the arcing members, and consequently maintains said arcing members at all times in proper alignment with each other and with the stationary arcing members.

The arrangement is also such that the current traverses the arcing members in series between the two stationary switch members 55 and, when the movable and stationary arcing members are separated, four circuit-interrupting arcs will be drawn in series.

The current path through the switch subsequent to the separation of the main 60 operating contacts is through bracket 18, which is electrically connected with one stationary switch member, the stationary arcing member 22 and its cooperating movable arcing member 74, the conducting rod 58 65 which connects electrically with the movable

arching member 72, through said member 72 and its cooperating stationary contact 32, the electrically-conducting bar 28, stationary arcing member 30 and its cooperating movable member 70, the second conducting bar 70 58 connecting contacts 70 and 68, the cooperating contacts 68 and 24, and bracket 20 to the outgoing stationary switch member.

1 claim:

1. An electric switch having a pair of spaced stationary switch members, a movable switch member including a rod disposed between said stationary switch members, a bridging member carried by the lower end of said rod below said stationary switch 80 members and adapted to bridge them, a plurality of arcing members carried by said rod and disposed symmetrically about and insulated from said bridging member, a corresponding plurality of stationary arcing 85 members cooperating with said movable arcing members and disposed symmetrically about said stationary switch members.

2. An electric switch having a pair of spaced stationary switch members, a movable 90 switch member including a rod disposed between and approximately in the plane of

said stationary switch members, a bridging member carried by the lower end of said rod below and approximately in the plane 95 of said stationary switch members and adapted to bridge them, a plurality of arcing members carried by said rod independent of said bridging member and disposed symmetrically about said bridging member, 100 a corresponding plurality of stationary arcing members cooperating with said movable arcing members and disposed symmetrically about said stationary switch members, each stationary switch member having a supporting and electrical connection with a stationary arcing member, and means electrically connecting said arcing members in series.

3. An electric switch having a pair of spaced stationary switch members, a pair 110 of stationary arcing members disposed on the same side of said switch members and in spaced relation therewith and also with each other and insulated from each other, supporting means connecting each arcing member with its cooperating switch member, a second pair of stationary arcing members disposed on the opposite side of said 115 stationary switch members, means electrically connecting said second pair of arcing members and supporting them in spaced relation with each other and with said stationary switch members, and a movable switch member including a rod disposed between said stationary switch members, a bridging member carried by the lower end of said rod below said stationary switch members and adapted to bridge them, a plurality of arcing members carried by said 120

100

110

rod below and arranged for cooperation with said stationary arcing members, and means electrically to connect certain of said movable arcing members.

5. A movable switch member for a multi-break electric switch comprising a vertically-disposed supporting member, a pair of horizontally-disposed insulating members carried by and on opposite sides of said supporting member, arcing members carried by both ends of each insulating member and means electrically connecting said arcing members in pairs.

10. A movable switch member for a multi-break electric switch comprising a supporting member, a bridging member carried thereby, a pair of insulating members carried by and on opposite sides of said supporting member and disposed transversely 20 of said bridging member, and electrically connected arcing members carried by the ends of said insulating members.

15. A movable switch member for a multi-break electric switch comprising a supporting member, a pair of insulating members carried by said supporting member on opposite sides thereof, arcing members carried by both ends of each insulating member, and means electrically connecting said arcing 30 members in pairs.

20. A movable switch member for a multi-break electric switch comprising a supporting member, a pair of insulating members carried by said supporting member on opposite sides thereof, arcing members carried by both ends of each insulating member, and means carried by each insulating member arranged electrically to connect the arcing members thereof.

25. A movable switch member for a multi-break electric switch comprising a supporting member, a pair of insulating members carried by said supporting member on opposite sides thereof, arcing members carried 35 by the ends of said insulating members, and means disposed within said insulating members arranged electrically to connect certain of said arcing members.

30. A rectilinearly movable switch member for a multi-break electric switch comprising a supporting member having a pair of oppositely-directed arms, an insulating member fixed to each of said arms, and arcing members fixed to both ends of each insulating member.

35. A rectilinearly movable switch member for a multi-break electric switch comprising a supporting member having a pair of oppositely-directed arms, an insulating member fixed to each of said arms, arcing members fixed to both ends of each insulating member, and means electrically connecting the arcing members of each insulating member.

40. A movable switch member for a multi-break electric switch comprising a supporting member having a pair of oppositely-directed arms, an insulating member fixed to each of said arms, arcing members carried at both ends of each insulating member, and independent means electrically connecting the arcing members of each insulating member.

45. A movable switch member for a multi-break electric switch comprising a supporting member having a pair of oppositely-directed arms, a tubular insulating member fixed to each of said arms, conducting rods passed through and extended beyond the ends of said tubular insulating members, and arcing members fixed to the extended ends of said rods.

50. A movable switch member for a multi-break electric switch comprising a supporting member having a pair of oppositely-directed arms, an electrically conducting rod carried by each arm and extended on both sides thereof, arcing members carried by the ends of said rods, and insulating means interposed between said rods and arms.

55. A movable switch member for a multi-break electric switch comprising a supporting member having two oppositely-directed sets of spaced arms, an insulating rod carried by each set of arms and extended transversely and on opposite sides thereof, arcing members disposed at the ends of each rod, and means electrically connecting certain of said arcing members.

60. A movable switch member for a multi-break electric switch comprising a supporting member having two oppositely-directed sets of spaced arms, an insulating rod carried by each set of arms and extended transversely and on opposite sides thereof, arcing members disposed at the ends of each rod, and means electrically connecting the arcing member of each rod.

65. A movable switch member for a multi-break electric switch comprising a supporting member having two oppositely-directed sets of spaced arms, an insulating rod carried by each set of arms and extended transversely and on opposite sides thereof, arcing members disposed at the ends of each rod, and means electrically connecting the arcing member of each rod comprising electrically conducting rods extended through said insulating rods and connected with said arcing members.

70. A movable switch member for a multi-break electric switch comprising a supporting member having two oppositely-directed sets of spaced arms, a tubular insulating rod carried by each set of arms, and extended transversely and on opposite sides thereof, an electrically conducting rod extended through and beyond both ends of each tubu-

lar insulating rod, and arcing members carried by the extended ends of each conducting rod.

18. A movable switch member for a multi-break electric switch comprising a supporting member having two oppositely-directed sets of spaced arms, an electrically conducting rod carried by each set of arms and extended transversely and on opposite sides thereof, arcing members carried by the ends of said rods, and insulating means interposed between said rods and said arms.

19. A movable switch member for a multi-break electric switch comprising a supporting member having two oppositely-directed sets of spaced arms, a bridging member disposed between the arms of said sets, an insulating rod carried by each set of arms and disposed transversely and on opposite sides of said bridging member, arcing members carried at the ends of said insulating rod and means to connect said arcing members in pairs.

20. A movable switch member for a multi-break electric switch comprising a supporting member having two oppositely-directed sets of spaced arms, a bridging member disposed between the arms of said sets, an insulating rod carried by each set of arms and disposed transversely and on opposite sides of said bridging member, electrically conducting rods disposed within said insulating

rods and extended outwardly beyond the ends thereof, and arcing members fixed to the ends of said conducting rods.

35

21. A movable switch member for a multi-break electric switch comprising a supporting member having two oppositely-directed sets of spaced arms formed with aligned square apertures in the ends thereof, a square insulating rod received in the aligned apertures in each set of arms, means to clamp said rods in the aforesaid relation, square electrically conducting rods disposed within said insulating rods and extended outwardly beyond both ends thereof, and arcing members fixed to the extended ends.

40

22. A contact structure for an electric switch comprising a contact member, a flat flexible member attached at one end to said contact member and having a struck-out intermediate portion and a supporting member attached to the other end of said flexible member, said supporting member having a projection overlying said flexible member and struck-out portion and adapted to engage said flexible member above said struck-out portion, and said projection having a recessed portion arranged to receive said struck-out portion.

45

In testimony whereof, I have signed my name to this specification.
